UNITED STATES PATENT OFFICE.

WILLIAM BALLARD MOORE, OF MIAMI, FLORIDA.

COMBINED ICE-TONGS AND WEIGHING-SCALE.

No. 876,213.

Specification of Letters Patent.

Patented Jan. 7, 1908.

Application filed September 5, 1907. Serial No. 391,460.

To all whom it may concern:

Be it known that I, WILLIAM BALLARD MOORE, a citizen of the United States, and a resident of Miami, in the county of Dade and State of Florida, have invented new and useful Improvements in a Combined Ice-Tongs and Weighing-Scales, of which the following is a full, clear, and exact description.

10 The invention relates to a form of tongs by means of which ice or other commodity may be weighed and its weight indicated.

I have illustrated one embodiment of the invention as showing a practical form, and 15 will particularly explain the same and point out the invention in the claims.

Reference is to be had to the accompanying drawings forming a part of this specification, in which similar characters of reference indicate corresponding parts in both views.

Figure 1 is an elevation of an ice tongs and weighing scales constructed in accordance with my invention; and Fig. 2 is a side view, 25 the parts being in section, on the line $x-x$ in Fig. 1.

In the form of the invention shown a pair of arms A is provided, having handles a and pivotally connected as at a', and these serve 30 as a support and carrier for a load-holder in the form of a pair of arms or tongs proper B, pivotally connected as at b, and provided with spurs b' for gripping a cake of ice, as indicated at 10. The connection between 35 the supporting arms A and the load-holder is effected through the medium of a spring balance, of which D indicates the graduated case, which is supported on the pivot a' that unites the arms A, and D' indicates the 40 spring rod of the balance carrying the usual pointer, said balance being constructed and operating in the well known manner.

The arms A are extended beyond their pivot, as at A', and are provided at their 45 lower ends with a means for establishing a connection between said arms and the arms or tongs B, this connection in the form shown consisting of inwardly extending guide loops C that loosely embrace the arms 50 B, so as to permit a free movement thereof relatively to the extensions A', when the tongs are opened or closed, or when said tongs move vertically to the extent permitted by the spring balance. One side C' 55 of each loop or guide is pivoted as at c, and is provided with a finger piece or projection c'

so that said side may be conveniently swung on its pivot to permit the complete disconnection between the extensions A' and the arms B. On the pivot stud of the swinging side C' a binding nut c' is provided to hold the swinging side in the closed position. By this construction it will be seen that the gripping arms B may be opened and closed by a suitable movement of the handled arms A, and when a cake of ice or other load is held by the arms B, the latter with their load will act on the spring balance in proportion to the weight of the load. The provision for detaching the operative connection between the gripping tongs B and their operating means, is to meet possible doubts on the part of a buyer as to whether the scale is being manipulated through the operating means, and the disconnecting of the parts so that the extensions A' may be swung to the positions indicated in the dotted lines in Fig. 1, makes it clear to the purchaser that there is no possibility of the spring balance being controlled by the vendor.

In order that the spring balance may be thrown out of action when desired and a fixed relation established between the load-holding tongs and the supports A, I provide a connecting bar E, which in the embodiment of the invention illustrated is pivoted at its lower end to the pivot b of the tongs, as clearly illustrated in Fig. 2, and said bar is provided with a slot e whereby the bar may be brought to the position indicated in Fig. 2, in which it is received on the stud f on the case D of the spring balance, a binding nut F serving to clamp the bar in the desired position and thus establishing a rigid connection between the pivots a' of the supporting and operating arms A and of the gripping tongs B, whereby the spring balance is thrown out of action and the load-gripping arms thus held against vertical movement relatively to the supporting arms A.

Having thus described my invention, I claim as new and desire to secure by Letters Patent,—

1. A carrying and weighing device, comprising a load-holder, a support therefor on which the load-holder is movable, a weighing means forming a connection between the load-holder and its support, and additional connecting means establishing a sliding connection between the said load-holder and its support.

2. A carrying and weighing device, com-

prising a load-holder, a support therefor on which the load-holder is movable, a weighing means forming a connection between the load-holder and its support, and additional connecting means establishing a sliding connection between the said load-holder and its support, said additional connecting means being detachable.

3. The combination of supporting means, pivoted gripping arms, means for suspending said gripping arms from said supporting means, the supporting means being capable of movement relatively to said gripping arms, and additional connections between said supporting means and the gripping arms whereby a movement of the supporting means will serve to open or close the gripping arms, said connections being detachable to free the gripping arms from the control of the supporting means.

4. An ice tongs, comprising pivoted carrier arms, pivoted gripping arms for engaging a block of ice, weighing devices arranged in connection with the said gripping arms to indicate the weight of the load carried thereby, and operative connections between the carrier arms and gripping arms.

5. An ice tongs, comprising pivoted carrier arms, pivoted gripping arms suspended from the pivot of the carrier arms, and connections between said carrier arms and gripping arms at a point removed from the pivot

of the latter to open and close the gripping tongs by movements of the carrier arms, said connections being detachable.

6. Tongs comprising two pairs of pivoted arms, one pair and the pivot thereof being movable relatively to the other pair, and weighing means forming a connection between said pairs of arms.

7. Tongs, comprising a pair of pivoted carrying arms, a separate pair of pivoted gripping arms movable with their pivot relatively to the carrying arms, a weighing means interposed between said pairs of arms, and a fastener for locking one pair of arms in fixed relation to the other.

8. The combination of a carrier comprising a pair of pivotally connected arms, a load-holder comprising a separate pair of pivotally connected arms, the latter pair having respectively a sliding movement on the arms of the first pair and controlled by said carrier arms to be opened or closed, and a weighing device establishing connection between the respective pivots of said arms.

In testimony whereof I have signed my name to this specification in the presence of two subscribing witnesses.

WILLIAM BALLARD MOORE.
